[57] CLAIM

The ornamental design for display unit, as shown and described.

DESCRIPTION

FIG. 1 is a perspective view of a display unit showing my new design;

FIG. 2 is a top plan view thereof;

FIG. 3 is a front elevational view thereof the opposite side being a mirror image thereof;

FIG. 4 is a left end view thereof;

FIG. 5 is a right end view thereof;

FIG. 6 is a bottom view thereof;

FIG. 7 is a cross-sectional view taken along lines 7—7 of FIG. 3; and,

FIG. 8 is a cross-sectional view taken along lines 8—8 of FIG. 3.

The broken line showings of a partial display base in FIG. 1 and of the displayed food items in FIGS. 3-5 are for illustrative purposes only and form no part of the claimed design.
